UNITED STATES PATENT OFFICE.

FREDERICK H. BARZ, OF VENTURA, IOWA.

HAY-DISTRIBUTER.

1,259,071.

Specification of Letters Patent. Patented Mar. 12, 1918.

Application filed May 11, 1916. Serial No. 96,824.

To all whom it may concern:

Be it known that I, FREDERICK H. BARZ, a citizen of the United States of America, residing at Ventura, in the county of Cerro 5 Gordo and State of Iowa, have invented certain new and useful Improvements in Hay-Distributors, of which the following is a specification, reference being had therein to the accompanying drawing.

10 This invention relates to hay forks, and has for its object, the production of an efficient hay fork for facilitating the distribution of hay upon a mound.

Another object of this invention is the 15 production of an efficient means whereby the tipping of the hay distributing fork will be regulated to alternately drop the hay upon opposite sides of the hay fork.

With this and other objects in view, this 20 invention consists of certain novel constructions, combinations, and arrangement of parts, as will be hereinafter fully described and claimed.

In the accompanying drawings:

25 Fig. 1 is a side elevation of the tipping fork as applied to a barn or other place of storage for hay.

Fig. 2 is a side elevation of the lower portion of the supporting standard showing the 30 fork partially dumped toward one side of the standard.

Fig. 3 is an enlarged transverse longitudinal section through the supporting standard showing the tripping trigger for the hay distributing fork in top plan.

Fig. 4 is a section through the trigger and supporting means therefor.

Fig. 5 is a perspective view of the pivotally mounted trigger.

40 Fig. 6 is a perspective view of the latch device for holding the trigger in a set position.

Fig. 7 is an enlarged sectional view through one of the hangers for holding the fork in a 45 set position upon the track.

Fig. 8 is a vertical section through the truss of the hanger showing an end view of the front hanger member.

Fig. 9 is a detail perspective of the clamping plate used in connection with the hanger plate shown in Fig. 7.

50 Referring to the drawings by numerals, it will be seen that the present device is susceptible of being used in a barn or other place of storage for hay, and within the barn or other place of storage is carried a track 1,

which preferably extends longitudinally of the barn. A hanger is suspended from the track 1, and comprises a forward hanger member 2 and a rear hanger member 3. The 60 forward hanger member 2, comprises a pair of parallel plates 4 provided with overhanging ends 5. A roller 6, is journaled between the parallel plates 4 and over this roller travels the shifting cable 7. The forward 65 hanger 2 and the rear hanger 3 are connected by means of a truss member 8 being twisted at its center portion to form a support for the main supporting standard 9.

The rear hanger 3 comprises a pair of parallel plates 10 which are bent inwardly at their lower ends as indicated at 11 for firmly clamping around the truss member 8. The upper ends of the parallel members 10 are bent inwardly as indicated at 12 overhanging the track 1. The bracket 13 is adjustably secured to one of the side members 10 and through this bracket 13 passes an adjustable rod 14 which is threaded at its upper end to facilitate the adjustment of the 70 rod 14 within the bracket 13. A clamping plate 15 is also provided with a rounded neck portion 18 intermediate its ends for traveling in the longitudinally extending slot 19 formed in the opposite parallel portions 10. The projecting end 20 of the clamping plate 15 overhangs the bracket 13 75 so as to be readily engaged by the upper end of the rod 14. This clamping plate 15 passes under the track 1, and it will be seen that 80 this clamping plate 15 may be firmly forced into engagement with the track 1, to hold the hay distributing fork in a set position upon the track 1. The reduced portion 16 of the plate 15 is held in the aperture 17 by 85 means of the vertically sliding angle plate 21 which angle plate 21 is provided with an angle foot 22 for facilitating the sliding of the plate 21 upon one of the parallel members 10. The plate 21 is firmly held in engagement with one of the side members 10 90 by means of the bolt 23.

The rod 14 is preferably long enough so as to allow the hay distributing fork to be locked upon the track 1 at the desired place 105 by the operator of the hay distributing fork. The main supporting rod 9 carries at its lower end a pair of spaced brackets or bracket members 24 which members constitute a support for the anchoring rod 25. 110 The anchoring rod 25 is provided with an angular end 26, which overhangs the upper

bracket 24 so as to limit the downward movement of the anchoring rod 25. The upper bracket 24 is provided with a folded end 27 through which the main supporting rod 9 passes, and this folded end 27 assists in holding the anchoring rod 25 in its correct position. A hay fork supporting bracket 28 is carried by the main supporting rod 9 and is rotatably mounted thereon. A collar 29 is anchored to the supporting rod 9 in any suitable or convenient manner upon each side of the bracket 28 for holding the bracket 28 in a set position upon the main supporting rod 9. A hay fork 30 is secured to the bracket 28 and comprises a transversely extending member 31 which transversely extending member 31 is provided with a pair of rearwardly extending ears 32, having a pivotal connection 32^a to the bracket 28.

20 The central tooth-connecting member 33 is carried by the fork and the bracket 34 is connected to the member 33 and to this bracket 34 is connected a link 35 by means of a bolt 36. The lower end of the link 35 is pivotably connected to a vertically extending bolt 37 which bolt has its lower head-portion 38 secured in the folded end 39 of the bracket 40 carried by the lower end of the main supporting rod 9.

25 A trigger-rod 41 is carried by the bolt 37 as is illustrated in Fig. 2 and a coil spring 42 is wound around the bolt 37 and engages the rear end of the rod 41 as is clearly illustrated in Figs. 1—2— and 3. The trigger-bar 35 or rod 41 is preferably reduced as indicated at 41^a when passing through the bolt 37. The free ends of the spring 42 are hooked around the lower end of the supporting rod 9 as illustrated clearly in Fig. 1. A trigger-latch 43 is pivotably secured to the rod 41 so as to have a vertical swinging movement and this latch is of a substantially U-shaped structure having a bifurcated end 44 which straddles the trigger-rod 41 in such a manner as to allow the latch 43 to swing upwardly out of engagement with the main supporting rod 9 as above cited.

30 This latch member 43 is adapted to be swung upon the trigger-rod 41 and controls the dumping of the hay fork. A locking frame 45 is pivotally secured to the trigger-rod 41 by means of a pivot pin 46 and this locking frame 45 is provided with a projecting end 47 which end is adapted to engage the notched ends 48 of the latch 43 and hold the latch in a vertical position as illustrated clearly in Fig. 4. The projecting end 47 is provided with a downwardly extending spur 49 which extends transversely of the projecting end 47.

35 A spring 50 is carried by the trigger-rod 41 and is wound around the transversely extending pin 51 of the frame 45. The outer end 52 of the spring 50 is adapted to engage the trigger 43 and normally urge the same

downwardly and into engagement with the main supporting rod 9 when the trigger 43 is disengaged from the projecting end 47 of the frame 45.

A projecting finger 53 is supported by the rod 9 below the trigger-rod 41 in such a position as to engage the spur 49 and force the projecting end 47 of the frame 45 out of engagement with the trigger 43 thereby causing the trigger 43 to be thrown downwardly 75 by means of the spring 52. The finger 53 extends on a line with the bracket 40 so as to be in an exact central position relative to the rod 9 whereby the spur 49 will be only engaged by the finger 53 when the fork 30 assumes its normal horizontal position.

A pair of laterally extending upwardly curved arms 54 are carried by the standard 9 adjacent the point which is adapted to be engaged by the trigger 43 and these arms 85 are formed on the arc of a circle so as to allow the trigger 43 to travel thereon and be forced to a vertical position as is illustrated in dotted lines in Fig. 1 thereby causing the locking frame 45 to hold the trigger 43 in 90 a vertical position until the fork assumes its normal horizontal position.

When the latch 43 is positioned in the manner illustrated in Fig. 3, the fork will dump toward the right as soon as the weight 95 of a load of hay has been placed thereon. When the latch 43 is placed upon the opposite side of the main supporting rod 9 so as to extend in a horizontal position, the fork will dump in the opposite direction or toward the left of the supporting rod 9. Owing to the fact that as the fork dumps toward one direction, the latch 43 will be locked in a vertical position, the latch 43 will be caused to drop upon the opposite side 100 of the supporting rod 9 due to the momentum which the fork will gather when returning to its normal horizontal position. This is caused by the finger 53 engaging the spur 49 and releasing the projecting end 105 47 from the latch 43 whereupon the latch 43 will be thrown to a horizontal position by means of the spring 52. It should be understood that the latch 43 will not begin to drop to a horizontal position until after the locking frame 45 has passed the finger 53 and this will cause the latch 43 to drop upon opposite sides of the supporting rod 9 at alternate times.

A spring supporting collar 55 is carried 120 by the main supporting rod 9 and this collar is provided with a downwardly extending hook 56, which engages the upper end of the spring 57. This spring 57 engages the collar 58 carried by one of the teeth of the hay 125 distributing fork and this spring 57 returns the fork to its normal position after the hay has been removed or distributed therefrom.

The operation of the device is as follows:

As a load is dumped upon the fork 30 the 130

weight of the load tends to cause the fork to swing downwardly on the pivot 32^a, against the tension of the spring 47. The fork however in its downward movement, is 5 forced to swing to one side by the rod 35 which rotates about the axis of the bolt 37 as a center, while the fork swings about the support 9 as a center. The spring 42 tends to prevent the turning of the bolt 37 and hence 10 the rotation of the fork. Said springs 42 are sufficiently strong to prevent rotation under the weight of the fork alone, but will allow the fork to rotate under the additional weight of a load to be placed thereon. The 15 latch 43 by being raised to a vertical position upon each swing of the fork 30, will be caused to alternately drop upon opposite sides of the supporting rod 9 due to the fact that the finger 53 will release the trigger 20 43 from the frame 45 as the trigger bar 41 is passing the center of the rod 9.

From the foregoing description it will be seen that a very simple and efficient means has been produced for causing the hay fork 25 to automatically and alternately dump in opposite directions.

The present invention is an improvement upon my previous application bearing Serial Number 701099, filed June 1st, 1912, 30 and allowed November 28th, 1913. The special improvements in the present invention over my previous invention resides in the means for automatically and alternately dumping the fork in opposite directions.

35 It, of course, should be understood that the spring 52 is necessarily formed of fine spring wire as shown clearly in Fig. 1 of the drawing. The spring 52 is, however, shown slightly exaggerated in size in Fig. 4 40 but it is desired to point out that this spring is necessarily formed of fine spring wire but is only wound around the pin 51 with one convolution in order that the frame 45 may operate. This construction of the spring 52 will 45 permit sufficient yielding movement for the frame 45 to accomplish the desired result.

What I claim as my invention is:—

1. A hay distributing device comprising a support, a standard carried thereby, a 50 fork mounted for horizontal swinging movements thereon, and means connecting the fork to the standard to cause the fork to alternately and automatically swing and dump toward different sides when a load is delivered thereon.

2. A device of the class described comprising a support, a main supporting standard carried thereby, a hay distributing fork 55 rotatably mounted upon said main supporting standard, trigger means carried by said fork, and means carried by said supporting standard and coöperating with said trigger means for causing said fork to alternately and automatically dump toward opposite sides when a load is placed upon said fork.

3. A device of the class described comprising a support, a main supporting standard carried thereby, a hay distributing fork rotatably mounted upon said main supporting standard, means carried by said standard and engaging said fork for causing the same to dump as said fork is swung upon said standard, trigger means carried by said fork, and means carried by said standard and coöperating with said trigger means for 70 causing said fork to automatically and alternately dump upon opposite sides of said standard. 75

4. A hay distributing device of the class described comprising a support, a standard 80 suspended from said support, a hay distributing fork pivotably mounted upon said standard and capable of being swung thereon, means associated with said standard and engaging said fork for causing said fork to 85 automatically and alternately dump toward opposite sides as the same is swung upon said standard, and means for returning said fork to its normal position after a load has been distributed therefrom. 90

5. A hay distributing device of the class described comprising a support, a hay fork rotatably mounted thereon, means for causing said fork to dump as the same is rotated, a pair of laterally extending upwardly curved arms carried by said support, a trigger coöperating with said fork for controlling the swing thereof, said trigger adapted to travel upon said arms whereby the same will be thrown in an upward 95 position as said fork is rotated, and means for locking said trigger in a vertical position. 100

6. A device of the class described comprising a support, a dumping fork rotatably 105 mounted thereon, means for causing said dumping fork to dump as the same is rotated upon said support, laterally and forwardly extending upwardly curved arms carried by said support, a trigger coöperating 110 with said fork, a latch carried by the outer end of said trigger, yieldable means for normally exerting a downward pressure upon said latch, a locking frame pivotably mounted upon said trigger and engaging 115 said latch for holding the same in a vertical position, said arms adapted to raise said latch to a vertical position, and means carried by said support and engaging said locking frame for allowing said latch to 120 fall to a horizontal position thereby preventing the rotation of said fork in one direction.

7. A device of the class described comprising a support, a dumping fork rotatably 125 mounted thereon, means for causing said dumping fork to dump as the same is rotated upon said support, laterally and forwardly extending upwardly curved arms carried by said support, a trigger coöperat- 130

ing with said fork, a latch carried by the outer end of said trigger, yieldable means for normally exerting a downward pressure upon said latch, a locking frame pivotably mounted upon said trigger and engaging said latch for holding the same in a vertical position, said arms adapted to raise said latch to a vertical position, a finger carried by

said support, said locking frame provided with a depending spur adapted to be engaged by said finger for releasing said locking frame from said latch and allowing said latch to fall to a horizontal position. 10

In testimony whereof I hereunto affix my signature.

FREDERICK H. BARZ.
